UNITED STATES PATENT OFFICE.

HERBERT ALEXANDER THOMPSON, OF MORPETH, ENGLAND, ASSIGNOR OF ONE-HALF
TO SWINNEY BROTHERS LIMITED, OF MORPETH, ENGLAND, A BRITISH COMPANY.

FURNACE FRONT.

Application filed December 26, 1924, Serial No. 758,187, and in Great Britain November 19, 1924.

This invention relates to furnace fronts for furnaces working under natural, assisted, or closed stokehold draught and the invention has for its object to provide an improved furnace front for such furnaces of the type which are convertible for burning either coal or oil or may be used for burning coal and oil simultaneously.

The improved furnace fronts are also of the type wherein oil burners fitted with coaxial air directing cones are arranged at an angle in relation to a central coal burning fire door.

A furnace front of the type referred to and made in accordance with the present invention comprises the combination with the fire opening and an air directing cone of an intermediate angular or wedge shaped filling in piece or extension from one of said parts whereby the said air directing cone is mounted upon the fire opening in fixed angular relation thereto.

As an example,—two air directing cones may be employed each provided with an outwardly extending angular or tapered boss, the outer face of which fits against the side of the fire opening and is secured thereto by bolts or studs, or other such like fastenings.

The said air directing cones are preferably provided with an oblique circumferential flange adapted to fit against the inside face of the inner plate of the furnace front so as to make an air tight joint therewith assisted if required by interposed packing material.

A furnace front having two air directing cones, made and fitted as above mentioned, may be provided with an air chamber divided into right and left hand chambers by a central division plate so that each air directing cone and its oil burner are located in or fed by separate air chambers.

Dampers such as hereinafter described may be fitted to the chambers of the furnace front, the fire door and the ash pit cover plate which is used when firing with oil.

The accompanying drawings illustrate one construction of improved furnace front carried out in accordance with the present invention,

Fig. 1 is a front elevation half in section,
Fig. 2 is a sectional plan,

Fig. 3 is a central vertical section of Fig. 1, on line 3—3.

Fig. 4 is a sectional detail showing a coal burning dead plate fitted to the furnace front,

Fig. 5 is a separate sectional view of one of the hinged dampers.

Fig. 6 is a sectional detail showing a cover plate fitted to the oil burner air cones when the furnace is being fired with coal alone,

Figure 7 is a detail plan view of one of the directing cones.

Figure 8 is a detail plan view of the same, and

Figure 9 is a vertical section through the furnace front taken transversely of the furnace and showing a modification in the frame structure.

In the construction shown, *a* is the air director, or cone, hereinafter referred to as the air directing cone, which may be of any suitable shape, to suit the space available.

In order to ensure accuracy in the setting of these air directing cones *a* so that they will properly register with the axes of the oil burners *b* the side of each air directing cone *a* is made with an outwardly projecting angular or tapered boss *a'* which is arranged to be secured to the wall or side of the fire opening *d*, by means of bolts or studs *d'*, or other such like fastenings.

The said air directing cones *a* are each provided with an oblique flange *e* adapted to fit against the inside face of the inner plate *c* of the furnace front.

This arrangement ensures perfect setting of the parts and enables the furnace front to be assembled all ready for fitting to the inner steel plate *c* instead of the cones, having to be attached to the said plate *c* as is usually the case.

The small oblique flange *e* abuts against the inner side of the plate *c* and maintains an air tight joint therewith. If required suitable jointing material may be inserted between the two faces.

The body *f* of the furnace front is preferably made with the fire opening *d* and a division plate *g* in one casting, but if desired for convenience in the manufacture, as shown in Figure 9, the casting may consist of right and left hand portions, each cast with a vertical plate which when brought together and the parts bolted up, as at *f'*, form one complete semicircular front with a division plate *g*.

The underside of the body *f* of the fur-

nace front is preferably made with a flange such as *h*, for the purpose of securing the casting to the inner steel plate *c* and also in carrying with the same bolts or studs or the dead plate *i* (Fig. 4) for use when coal burning.

The necessary air for combustion in the oil burners which are situated in the air directing cones *a* is admitted to the inside of the air chambers on the body of the furnace front by means of pivoted plates or dampers *j* which are so mounted that their lower edges open inwards and direct the air downwards.

These regulating dampers *j* are mounted on square bars or hinges *j'*, the ends of which are made circular to act as pivots or hinge pins and are received within securing lugs *k* fastened to the front of the body *f* by means of studs or bolts.

A small knob or handle *l* is fitted to the damper plate *j* for the purpose of operating the same, and thumb screws *m* are also provided for the purpose of adjusting and rigidly securing the damper plate either in the open, closed, or any intermediate position.

Suitable sight holes *n* are fitted consisting of mica, plates or other transparent material so that the attendant may be able to observe the flame at the burner end, these sight holes *n* being situated in the front face of the casting *f* so that they are within the diameter or area of the air directing cones *a*.

The fire opening *d* is closed by means of any suitable type of coal burning door, that in the drawing being of the hinge type. To this coal door however is fitted a small pivoted damper *j* similar to that above de-

scribed. Below this damper *j* is arranged a small hinged door *o* which is provided principally as a means of access for passing in a lighted torch when lighting up the oil burners. This door *o* may be fitted with mica plates or other transparent material to form a sight hole.

A semi-circular plate *p* is provided for the purpose of closing up the lower half of the furnace opening when oil burning. This plate *p* has fitted to it a frame *q* which forms an air opening through the plate. The said air opening is controlled by means of another pivoted damper *j* such as previously described.

To the frame *q* are also fitted lifting handles *q'*, these handles being preferably of mild steel secured in the frame *q* when casting the same.

When it is desired to burn coal only with the improved furnace front, closing plates *r* are employed for covering the inner end or opening of the air cones *a*; these plates *r* are of similar shape to the air cones and they are provided with holes *r'* to allow of a small circulation of air through these

plates to keep the same cool. The plate *r* may be secured in position by the simple arrangement of bolt *r'* carried through the burner holder *b'* after the burner *b* has been removed.

The operation of the improved furnace fronts for oil burning is as follows:—

Suitably heated oil having been led to the burners *b* which are inserted through the cones *a*, and which burners may be of any desired type, the air control dampers *j* are opened to the desired extent which allows air to pass within air chambers of the body *f*. These pivoted dampers *j* cause the air to be thrown against the plate *c* so that the air is caused to circulate over the surface of the said plate and keep the same cool.

The air then passes down within the body *f* and having been raised in temperature through its circulation over the plate *c* is then free to pass through the cones *a* and mix with the oil spray from the burners.

The ashpit damper plate *j* is also opened a desired amount and this being hinged in an inward and upward direction causes the air to pass upwards towards the burners *b*.

A lighted torch is inserted through the small door *o* to start combustion.

The small control damper *j* in the fire door is provided to allow a small quantity of air to circulate within the coal fire opening *d* to destroy any vacuum effect which may arise through this opening being towards the rear of the burners, it having been found that where this door is hermetically sealed there is a tendency for the flame from the burners to be drawn back to the fire opening and cause damage through local heating.

It has been found that the necessary small quantity of air may be suitably admitted through the damper *j* in the fire box.

What I claim as my invention and desire to secure by Letters Patent is:—

1. A furnace front of the type referred to comprising the combination of a furnace front formed of an inner plate provided with apertures and an outer casting comprising the firing opening and enclosing an air heating chamber, oil burners located one on each side of the firing opening, air directing cones arranged coaxially with said oil burners and each provided with an outwardly extending angular boss and an outer oblique circumferential flange, means for attaching said angular bosses to the sides of the fire opening casting whereby said air directing cones are mounted in fixed angular relation to the sides of the fire opening casting and with their oblique circumferential flanges fitted against the inside face of the inner plate of the furnace front.

2. A furnace front of the type referred to comprising the combination of a furnace front formed of an inner plate provided

with apertures for receiving the air directing cones and an outer casting comprising a firing opening and enclosing an air heating chamber divided by a central partition located above the firing opening, oil burners located one on each side of the firing opening air directing cones arranged coaxially with said oil burners and each provided with an outwardly extending angular boss and an outer oblique circumferential flange, means for attaching said angular bosses to the sides of the fire opening casting whereby said air directing cones are mounted in fixed angular relation to the sides of the fire opening casting and with their oblique circumferential flanges fitted against the inside face of the inner plate of the furnace front.

3. A furnace front of the type referred to comprising the combination of, a furnace front formed of an inner plate provided with apertures and an outer casting comprising a firing opening and enclosing an air heating chamber divided by a central partition located above the firing opening, a downwardly extending flange on the lower part of the air chamber casting and means for securing said flange to the inner plate of the furnace front and bolts for detachably securing a coal burning dead plate to the inner side of the said inner plate and to said downwardly extending flange, oil burners located one on each side of the firing opening, air directing cones arranged coaxially with said oil burners and each provided with an outwardly extending angular boss and an outer oblique circumferential flange, means for attaching said angular bosses to the sides of the fire opening casting whereby said air directing cones are mounted in fixed angular relation to the sides of the fire opening casting and with their oblique circumferential flanges fitted against the inside face of the inner plate of the furnace front.

4. A furnace front of the type referred to comprising the combination of, a furnace front formed of an inner plate provided with apertures and an outer casting comprising a firing opening and enclosing an air heating chamber divided by a central partition located above the firing opening, a downwardly extending flange on the lower part of the air chamber casting and means for securing said flange to the inner plate of the furnace front and bolts for detachably securing a coal burning dead plate to the inner side of the said inner plate and to said downwardly extending flange, oil burners located one on each side of the firing

opening, air directing cones arranged coaxially with said oil burners and each provided with an outwardly extending angular boss and an outer oblique circumferential flange, means for attaching said angular bosses to the sides of the fire opening casting whereby said air directing cones are mounted in fixed angular relation to the sides of the fire opening casting and with their oblique circumferential flanges fitted against the inside face of the inner plate of the furnace front, a detachable cover plate for the ash pit opening, pivoted air admission dampers for the air chamber the fire door and the ash pit cover plate used for oil burning, consisting of plates mounted on hinged bars and provided with operating knobs and adjusting thumb screws.

5. A furnace front of the type referred to comprising the combination of, a furnace front formed of an inner plate provided with apertures and an outer casting comprising a firing opening and enclosing an air heating chamber divided by a central partition located above the firing opening, a downwardly extending flange on the lower part of the air chamber casting and means for securing said flange to the inner plate of the furnace front and bolts for detachably securing a coal burning dead plate to the inner side of the said inner plate and to said downwardly extending flange, oil burners located one on each side of the firing opening, air directing cones arranged coaxially with said oil burners and each provided with an outwardly extending angular boss and an outer oblique circumferential flange, means for attaching said angular bosses to the sides of the fire opening casting whereby said air directing cones are mounted in fixed angular relation to the sides of the fire opening casting and with their oblique circumferential flanges fitted against the inside face of the inner plate of the furnace front, a detachable cover plate for the ash pit opening, pivoted air admission dampers for the air chamber the fire door and the ash pit cover plate used for oil burning, consisting of plates mounted on hinged bars and provided with operating knobs and adjusting thumb screws, means for securing the detachable ash pit cover plate beneath the edge of said downwardly extending flange on the furnace front casting and clamps mounted on said downwardly extending flange and bearing on the detachable ash pit cover plate.
